[57] CLAIM

The ornamental design for a vest mounted sound system, as shown and described.

DESCRIPTION

FIG. 1 is a front elevational view of a vest mounted sound system showing my new design;

FIG. 2 is a side elevational view thereof;

FIG. 3 is a rear elevational view thereof;

FIG. 4 is a top plan view thereof;

FIG. 5 is a bottom plan view thereof;

FIG. 6 is an elevational view taken along lines 6—6 in FIG. 2; and,

FIG. 7 is an elevational view taken along lines 7—7 in FIG. 2.

The cross-hatch shading shown on the straps in all views is understood to repeat throughout the indicated area.

FIG. 1

FIG. 2

FIG. 3

FIG. 4FIG. 5FIG. 7FIG. 6
